CHRISTMAS TREE BASE

Henry Anthony Cousland, El Monte, Calif.

Application November 9, 1953, Serial No. 27,520

Term of patent 14 years

(Cl. D35—3)

To all whom it may concern:

Be it known that I, Henry Anthony Cousland, have invented a new, original, and ornamental Design for a Christmas Tree Base, of which the following is a specification, reference being made to the accompanying drawing, forming a part hereof.

I claim:

The ornamental design for a Christmas tree base, as shown.
